UNITED STATES PATENT OFFICE.

GUSTAV SCHOENEMANN, OF NEW YORK, N. Y.

DESIGN FOR A JEWEL OR SILVER-WARE BOX.

Specification forming part of Design No. 5,833, dated April 30, 1872.

Specification describing a new and original Design for a Jewelry and Silver-Ware Box, designed by GUSTAV SCHOENEMANN, of the city, county, and State of New York.

The drawing represents a perspective view of my new design for a box.

This invention relates to a new design for a jewelry and silver-ware box; and consists in making its top arched, so that the upper edges of its sides and ends are also arched, though it is higher in the middle than at the higher parts of the sides and ends, and in making its

corners rounded. The outline of the top will thereby be gracefully undulating, as shown.

Having thus described my design, I claim as new and desire to secure by Letters Patent—

The design for a jewelry and silver-ware box, as shown.

G. SCHOENEMANN.
